UNITED STATES PATENT OFFICE.

ALEXANDER LAGERMAN, JR., OF LERUM, AND GUSTAF HJALMAR LINDSTRÖM, OF GOTTEBORG, SWEDEN, ASSIGNEES TO AKTIEBOLAGET PRINCEPS, OF STOCKHOLM, SWEDEN, A CORPORATION OF SWEDEN.

PAPER-FEEDING DEVICE FOR AUTOMATIC PLATEN PRINTING-PRESSES AND THE LIKE.

1,099,552.

Specification of Letters Patent.

Patented June 9, 1914.

Application filed July 29, 1913. Serial No. 781,825.

To all whom it may concern:

Be it known that we, ALEXANDER LAGERMAN, Jr., a subject of the King of Sweden, and resident of Villa Alexandra, Lerum, 5 in the Kingdom of Sweden, and GUSTAF HJALMAR LINDSTRÖM, a subject of the King of Sweden, and resident of Berzeliigatan No. 9, Gottenborg, in the Kingdom of Sweden, have invented certain new and useful 10 Improvements in Paper-Feeding Devices for Automatic Platen Printing-Presses and the like, of which the following is a specification, reference being had therein to the accompanying drawings.

15 This invention relates to means for moving the paper in automatic platen printing presses and the like, especially for moving the paper from the feed table to the platen. The said means consist of a transporter oscillating around a shaft or moved and guided in any other suitable manner, which 20 transporter is provided with a row of grippers, which seize the paper sheet by engaging its edge, which previously has been somewhat raised from the pile of paper sheets. The said grippers are held in closed 25 position by spring pressure, so that the seized paper sheet is carried by the transporter, when moved to the platen, which is provided with a suitable gripping device, 30 which receives the sheet and then holds the same.

The invention is based upon the fact that the thickness of the paper generally varies 35 considerably, from thick carton to the thinnest paper or so called tissue-paper. In order that the paper sheet may be located in the desired proper place on the platen, which is necessary for the effecting of an accurate print, the transporter may not release the sheet directly at its returning but somewhat later, the sheet being then pulled from the said grippers. The pressure exerted by the springs must however be so great, that it is sufficient for the seizing of the thickest paper to be printed, which on the other hand results in the sheet, when thin, easily being rendered uneven by the stretching during the releasing operation.

40 Through the present invention the object is gained, that even the thinnest sheet remains in a flat condition on the platen.

The invention consists in the said spring pressure being removed, as the sheet leaves

the grippers, and in the grippers being provided with a thin, feeble plate spring, located between the jaws of the grippers. As the grippers are opened *i. e.* as the jaws of the grippers are moved from each other, the said thin springs still act upon the sheet, but owing to the fact that the said springs are very feeble, the sheet can now be drawn from the grippers without being subjected to any stretching, which would render the same uneven. The described device is adjustable in such manner, that the greater spring pressure is not removed, when thick paper is printed.

45 In the accompanying drawings Figure 1 is a side view of the transporter, the platen and some other parts, shown schematically. Fig. 2 is a side view of a part of the transporter on a greater scale. Fig. 3 is a front view of the same parts. Figs. 4 to 8 inclusive are details.

50 The platen 1, Fig. 1, oscillates around the shaft 2 in the well known manner. The transporter mentioned above consists of two arms 3 which are fixed to the rocker shaft 4, actuated by a suitable crank and lever mechanism. The gripper mechanism consists of the side pieces 5, 5, see also Figs. 2 to 4 inclusive, pivoted to the arms 3 and forming extensions of the same, the cross-piece 6, arms 7, 7 projecting from the said cross-piece and forming one of the jaws of the 55 said grippers respectively, and of the two armed levers 9, 10, which are fixed to the shaft 8, journaled in the side pieces 5 and located opposite to the said arms 7 respectively. The longer arms 9 of the said levers form the movable jaws of the grippers and are acted upon by springs 11, located between the short arms 10 of the levers and the cross piece 6. The said springs 11 effect the 60 comparatively great pressure, mentioned above, for the closing of the grippers. The levers 9, 10 are slid on the shaft 8 and connected with the same by means of screws or pins 8* respectively. The openings provided 65 in the levers for the said screws or pins extend for a short distance around the shaft, so that there is provided a little play for the levers. On the shaft 8 a lever 12 or the like is provided, which when swung acts 70 upon the shaft by means of a clutch 13. A tension spring 14 or the like, connected with the lever 12 and a pin projecting from the

side piece 5, tends to swing the lever in the direction indicated by the arrow shown in Fig. 2. The said movement of the lever, transmitted through the shaft 8 and the levers 9, 10 counteracts the springs 11. An abutment or catching device is provided for the lever 12, formed by one 15 of the arms of a two armed lever, which is pivoted to the side piece 5 and the other arm 16 of which 5 during the movement of the transporter is acted upon by an abutment, located in its path, which abutment is provided on the platen and consists of a lever 17 or the like, which is adjustable, so that its action can 10 be suspended, if wanted. The position of the lever 17 is controlled by means of a screw 18, against which the lever is forced by a spring 19. The lever 12 is provided on its inner side with a projection or 15 shoulder 20 coöoperating with the lever 15, 16, so that the lever 12 occupies different positions, according as the lever 15, 16 is swung to the position, in which the lever 12 bears against the arm 15 by means of the said 20 shoulder, or is swung out of the said position, so that the action of the lever 12 (spring 14) on the springs 11 is suspended 25 or not suspended respectively.

In Figs. 5 and 6, which show the movable 30 jaw 9, 10 of one of the grippers, a thin plate spring 21 is illustrated, which is fixed to the jaw 9, 10 and, as the said jaw is swung from the stationary jaw 7 for a short distance, still is forced against the jaw 7 with 35 a slight pressure, suitably adapted for the holding of a thin paper sheet. On the platen a roller 22 or the like is provided. As the transporter passes the said roller 22 during its return movement toward the feed table, the roller 22 acts upon the top or rear end of the lever 12 and swings the lever in such direction, that the lever 15, 16, acted upon by a spring 28, will occupy the position shown in Fig. 2 and bear against the shoulder 20. When the lever 12 has been arrested 40 in the said manner, the springs 11 are no longer counteracted by the spring 14. On the one end of the shaft 8 there is an arm, provided with a projection, which slides 45 over a projection provided on an arm pivoted to the frame of the machine, as the grippers arrive to the raised edge of the sheet, so that the shaft is rotated and the grippers are opened for a moment. During 50 the continued movement the edge of the sheet enters the grippers, which are then closed. As the transporter is again moved forward and upward, the said projection of the transporter passes under the projection 55 of the arm pivoted to the frame, so that the said arm is raised and the grippers remain closed. The said device, though in a different form, is well known before. If now, when the transporter is moved upward, the 60 lever 17 has been brought into such posi-

tion, that it does not act upon the lever 15, 16, passing the same, no shifting of the latter is effected and the paper sheet is delivered to the platen without any reduction of the gripper pressure. The mechanism 70 acts in this manner, while ordinary stiff paper is printed. If on the other hand thin paper is used, the lever 17 is so shifted, that the lever 15, 16, passing the same, is swung in the direction indicated by the arrow in Fig. 2, so that it leaves the shoulder 20 and permits the spring 14 to counteract the springs 11. Owing to this fact the gripper pressure is reduced to the pressure exerted by the springs 21 and consequently 80 the paper sheet is drawn very easily from the transporter by the gripping device provided on the platen. The moment, in which the great gripper pressure is suspended, is regulated by bringing the lever 17 into different angular positions.

Two piles of paper sheets may be put into the machine and two sheets located abreast may be printed. For adjusting the gripper pressure to the paper sheets respectively the 90 shaft 8 is divided at its center into two parts. The said parts are provided at the adjacent ends with arms 25 and 26 respectively, Figs. 7 and 8, which arms are connected by a jaw nut 27 or the like in such manner, that the 95 arms and the parts of the shaft can be rotated with relation to each other, after the said screw has been untightened. The arms are then again connected by tightening the screw. Consequently, the parts 25 to 27 100 inclusive form a clutch of special type. Owing to the said arrangement the gripper pressure can be adapted for thick paper sheets, forming one of the piles, and for thin paper sheets forming the other pile 105 by so adjusting the parts of the shaft, with relation to which the jaws of the grippers are rotatable for some distance (as stated above at the description of the screw 8*) that, if the mechanism described above acts 110 at one of the piles formed by thin paper sheets, the pressure of the grippers at the other part of the shaft is sufficient for the thick paper sheets forming the other pile. Consequently, by the arrangement described 115 above gripper jaws 9, 10 and springs 11 respectively of such a stiffness may be used, that no slackness or defectiveness of any of the same is to be feared, all unsafeness concerning the durability of the mechanism being thus removed, which hardly would be the case, if the jaws proper of the grippers were rendered very yielding or very weak springs 11 were used.

The mechanism for effecting the described 125 unloading may easily be modified. The invention may be applied also to folding machines, ruling machines and other similar machines.

Having now described our invention, what 130

we claim as new and desire to secure by Letters Patent is:

1. In automatic platen printing presses and similar machines the combination with the transporter, grippers provided on the said transporter for the seizing of the paper sheets, the spring (11) for holding the grippers in closed position, and the shaft actuating one of the jaws of the said grippers, of a lever arm (12) provided on the said shaft, a catching device for the said arm, a spring (14) acting upon the said arm in such direction, that the action of the spring (11) is counteracted, if the said lever arm has been disengaged, as the paper sheet is to be delivered to the platen, and blade springs (21) having tensions less than the aforesaid spring 11 and arranged to be thrown into position by the spring 11 to act upon the paper sheet and, as the said disengagement has been effected, hold the sheet with slight pressure, substantially as described and shown in the accompanying drawings.

2. In automatic platen printing presses and similar machines the combination with the transporter, grippers provided on the said transporter for the seizing of the paper sheets, the spring (11) for holding the grippers in closed position, and the shaft actuating one of the jaws of the said grippers of a lever arm (12) provided on the said shaft, a catching lever arm (15, 16) pivoted to the said transporter, a spring (28) tending to move the said lever arm (15, 16) into position to catch the lever arm (12), an adjustable abutment (17) which is provided on the platen and can be located in the path of the said lever arm (15, 16) for disengaging the same, a spring (14) acting upon the lever arm (12) in such direction, that the action of the spring (11) is counteracted, if the lever arm (15, 16) has been disengaged, as the paper sheet is to be delivered to the platen, and blade springs (21) having tensions less than the aforesaid spring 11 and arranged to be thrown into position by the spring 11 to act upon the paper sheet and as the said disengagement has been effected hold the sheet with a slight pressure, substantially as described and shown in the accompanying drawings.

3. In automatic platen printing presses the combination with the transporter, grippers provided on the said transporter for the seizing of the paper sheets, the spring

(11) for holding the grippers in closed position, and the shaft actuating one of the jaws of the said grippers, of a lever arm (12) provided on the said shaft, a catching device for the said arm, a spring (14) acting upon the said arm in such direction, that the action of the spring (11) is counteracted if the said lever arm has been disengaged, as the paper is to be delivered to the platen, and an abutment (22), which is located in the path of the lever arm (12) and removes the said lever arm into its arrested position, as the transporter is moved to the feed table, and blade springs (21) having tensions less than the aforesaid spring 11 and arranged to be thrown into position by the spring 11 to act upon the paper sheet and, as the said disengagement has been effected, hold the sheet with slight pressure, substantially as described and shown in the accompanying drawings.

4. In automatic platen printing presses the combination with the transporter, grippers provided on the said transporter for the seizing of the paper sheets, the spring (11) for holding the grippers in closed position, and the shaft actuating one of the jaws of the said grippers, of a lever arm (12) provided on the said shaft, a catching device for the said arm, a spring (14) acting upon the said arm in such direction, that the action of the spring (11) is counteracted, if the said lever arm has been disengaged, as the paper sheet is to be delivered to the platen, the said shaft being divided transversely into two parts, rotatable with relation to each other and each carrying a set of grippers, means for connecting the said parts, and blade springs (21) having tensions less than the aforesaid spring 11 and arranged to be thrown into position by the spring 11 to act upon the paper sheet and, as the said disengagement has been effected, hold the sheet with slight pressure, substantially as described and shown in the accompanying drawings.

In witness whereof, we have hereunto signed our names in the presence of two subscribing witnesses.

ALEXANDER LAGERMAN, JR.
GUSTAF HJALMAR LINDSTRÖM.
